UNITED STATES PATENT OFFICE.

FRANCIS E. O'BRIEN AND LOUIS FREEMAN, OF NORTHAMPTON, MASSACHUSETTS; SAID FREEMAN, ASSIGNEE TO JOSEPH FREEMAN, OF BROOKLYN, NEW YORK.

BINDING POST.

Application filed March 25, 1925. Serial No. 18,144.

This invention relates to a binding post, and has for its principal object to provide a binding post to which a wire may be very quickly attached or from which the wire may be quickly detached.

Another important object of the invention is to provide a binding post which will firmly engage the wire so as to prevent its accidental displacement therefrom.

10 A still further very important object of the invention is to provide a binding post of this nature having an exceedingly simple structure which is easy to manipulate, one which is efficient and reliable, inexpensive to 15 manufacture, strong, durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

25 In the drawing:-

The figure is an elevation of the binding post embodying the features of our invention showing a portion thereof in section.

Referring to the drawing in detail, it will be seen that 1 designates a panel or any other suitable support through which is projected the post 2 preferably having the end thereof threaded as at 3 in order that nuts 4 may be engaged thereon, one on each side of the panel or support 1, thereby securely locking the post in place. This post is provided with a transversely extending opening 5 through which may be inserted a wire. The outer end of the post 2 has formed thereon a head 6 of insulating material being cylindrical in form, as indicated at 7, and provided with a milled flange 8 at its outer end in order that the post may be rotated and screwed through the panel if desired. A slid able member 9 is mounted on the post 2 and is substantially cup-shaped in formation including a cylindrical body 10 adapted

to slide over the cylindrical portion 7 of the head 6 and an apertured body 11 through which the post 2 extends. A flange 12 is mounted on the outer end of the cylindrical body 10 for abutting the flange 8, thereby limiting the outward movement of the slide-
able member 9. A coil spring 14 is disposed about the post 2 and impinges against the inner end of the head 6 and the bottom 11 of the slideable member 9. The spring 14 is tensioned to normally hold the slideable mem-
ber over the opening 5. Thus it will be seen that when the slideable member 9 is moved toward the flange 8 by engaging the fingers on the flange 12 that the wire may be passed through the opening 5, and then the slide-
able member may be released for binding against the wire so as to hold it securely in the post against accidental removal.

Having thus described the invention, what we claim as new is:—

In testimony whereof we affix our signatures.

FRANCIS E. O'BRIEN.
LOUIS FREEMAN.
